UNITED STATES PATENT OFFICE.

MIRIAM GROSS, OF CHICAGO, ILLINOIS, ASSIGNOR TO MATTHEW P. RAE, OF CHICAGO, ILLINOIS, TRADING UNDER THE NAME RAEDOR.

DESIGN FOR A DRESS.

52,268.

Specification for Design. Patented Aug. 20, 1918.

Application filed April 25, 1918. Serial No. 230,814. Term of patent 3½ years.

To all whom it may concern:

Be it known that I, MIRIAM GROSS, a citizen of the United States, residing at the city of Chicago, county of Cook, and State of Illinois, (whose post-office address is 927 Buena avenue, in said city,) have invented a new, original, and ornamental Design for a Dress, of which the following is a specification, reference being had to the accompanying drawing, forming part thereof.

The figure is front view of a dress, showing my new design.

I claim:

The ornamental design for a dress, as shown.

MIRIAM GROSS.
